CORSET

Jacob L. Alberts, Yonkers, N. Y., assignor to
Sidney S. Alberts, Yonkers, N. Y.

Application October 5, 1934, Serial No. 747,052

4 Claims. (Cl. 2—30)

This invention relates to foundation garments and more particularly concerns garments such as combined corsets and brassières which have connected portions for respectively confining and supporting different parts of the body.

Known foundation garments of the type which combine the functions of the corset and brassière are subject to the objection that they oppose the natural bending movements of the body. This either results in the displacement of one or both parts of the garment whereby its supporting functions are lost or impaired or in the tearing or stretching of the garment or of the stockings to which it is attached due to the strains set up by the bending movements.

It is the object of the present invention to provide a foundation garment of the type described which permits natural bending movements of the body without the displacement of the supporting portions of the garment from their proper supporting positions, and without straining, stretching or tearing the garment itself or other garments to which it may be attached. A further object of the invention is the provision of a foundation garment of this type in which the various parts are at all times held snugly against the body of the wearer and in which bending movements do not result in the folding or wrinkling of the garment parts. A still further object of the invention is the provision of a foundation garment comprising corset and brassière parts having their back sections connected by an elastically extensible connection which is completely concealed within or beneath one of the garment parts. The objects of the invention also include the provision of a combined corset and brassière garment in which the elastically extensible connection between the back sections of the corset and brassière parts prevents the upward sliding movement of the corset part due to bending movements of the body of the wearer.

The above and other objects of the invention are carried out in general by providing a foundation garment having its upper and lower parts designed respectively to support different parts of the body, such as a combined corset and brassière, and by providing an elastically extensible connection between the back sections of the upper and lower parts of the garment. With this arrangement, when the wearer bends forward the upper and lower parts of the garment remain in their proper supporting positions about the upper and lower parts of the torso respectively, and the elastically extensible connection between the back sections of the upper and lower garment parts is

extended to permit the bending movement without stretching, straining or tearing the garment itself or other garments to which it is attached. At the same time, the elastic connection holds the garment sections snugly against the body and prevents wrinkling or folding at the edges of the garment parts. In a preferred form of the invention, the back sections of the upper and lower parts of the garment are disposed in overlapping relation and the elastic connection between these sections is concealed within one of the back sections.

The invention will be best understood by reference to the accompanying drawings in which certain embodiments thereof have been illustrated. 15 In the drawings:

Figure 1 is a rear elevation of a foundation garment embodying the invention;

Figure 2 is an inside view of the garment of Figure 1 with the front section thereof opened out 20 to show the interior of the back section;

Figure 3 is a sectional view of the back section of the garment of Figure 1, taken along the line 25 3—3 of Figure 1 and viewed in the direction of the arrows;

Figure 4 is a sectional view of the garment of Figure 1, taken along the line 4—4 of Figure 1 and viewed in the direction of the arrows;

Figure 5 is a rear elevation of a modified form of foundation garment embodying the invention 30 with a portion of the back section broken away to show the interior construction; and

Figure 6 is an inside view of the back section of the garment shown in Figure 5.

Referring to the embodiment of the invention 35 shown in Figures 1 to 4, the garment comprises generally a lower or corset part C and an upper or brassière part B. The front section F of the garment, as shown in Figure 2, consists of integral or directly connected upper and lower parts, and is preferably formed of non-elastic material. Thus the lower part or panel 7 of the front section may comprise any suitable non-elastic fabric such as silk, satin or cotton cloth and the upper or brassière part 8 of the front section may be made 45 of lace, net or other light fabric. The upper and lower parts of the front section are suitably seamed together as shown at 9. An elastic gusset insert 10 is preferably provided at the lower edge of the lower panel 7 as shown. The side sections 50 11 and 12 of the lower or corset part C are preferably formed of elastic material, and as shown, these sections are seamed to the opposite edges of the back section 13 of the corset part of the garment. The side section 11 is also seamed to one 55

side of the corset front section 7, and the garment opens at the juncture of the side panel 12 and the front section 7 as shown.

The back section 13 of the lower or corset part 5 of the garment is preferably formed of a suitable non-elastic fabric and is provided with a lining 14 as shown in Figs. 2 and 3. The back section of the upper or brassière part of the garment is also made of non-elastic material, and as shown, 10 may comprise a central panel 15 of relatively heavy fabric and two side panels 16 and 17, seamed to the central panel and formed of lace, net or other light fabric which preferably matches the fabric of the front section 8 of the brassière 15 part. The lower edge of the back section of the brassière part extends down over the upper edge of the lower back section 13 in overlapping relation therewith, as shown in Fig. 1. The lower edges of the brassière side panels 16 and 17 are 20 stitched to the elastic lower side sections 11 and 12, as shown at 18, whereas the lower edge of the central back panel 15 is not attached to the lower part of the garment and lies in overlapping unconnected relation thereto.

25 The meeting edges of the back and front sections of the garment are provided with suitable detachable fastening means such as hooks and eyes as shown at 25. If desired, spaced vertical stays of whalebone, steel or the like may be employed to stiffen the lower or corset part of the garment, and stays of this nature have been shown at 26 and 27 in Fig. 4. Garters 28 of any desired type may be secured at spaced points along the lower edge of the front and back sections 7 and 13 of the corset part. The garment is preferably provided with shoulder straps 30 which extend between the front section 8 of the upper or brassière part and the center panel 15 of the back section of the brassière part as shown 35 in Figs. 1 and 2. The straps 30 may be connected to the back center panel 15 by means of elastic tapes 31.

In accordance with my invention, the back section of the upper or brassière part of the garment is yieldably attached to the back section of the lower or corset part thereof so that the upper and lower back sections are movable relative to each other and are at the same time securely connected and held snugly against the body in 40 all relative positions. This yieldable elastic connection may be effected in various ways. As shown in the drawings, the lower edge of the central back panel 15 of the upper or brassière part terminates in a central downwardly extending tab 19 which extends through a transverse slit or opening 20 in the back panel 13 of the lower or corset part of the garment. As best shown in Fig. 3, the upper or inner edge of the slit 20 may be stitched to the lining 14 of the lower back section as shown at 21 and the lower or outer edge of this slit may be suitably hemmed as shown at 22. The upper end of a band or strip 23 of elastic material is stitched to the lower end of the tab 19 and the lower end of this strip 23 is secured to the upper edge of a section of non-elastic material 24, the lower edge of which is attached to the lower seam 28 of the back panel 13.

With the above described arrangement, forward bending movement of the wearer does not tend to displace either the upper brassière part or the lower corset part of the garment, since the relative movement of the upper and lower parts of the torso about which these parts of the garment are secured merely results in the extension of the elastic connection between the two

garment parts. The yieldable back connection avoids straining or tearing of the garment when the body bends, and since the lower or corset part does not move upwardly along the body, no undue strains are imposed on the stockings or garters connected thereto. When the wearer straightens up the elastic connection contracts and keeps the lower edge of the brassière back section in snug and smooth fit against the back of the body.

The garment of Figs. 5 and 6 has the same front and side construction as that described above in connection with the garment of Figs. 1 to 4. The downwardly extending tab 19' of the central back section 15' of the upper or brassière part B' is connected to an elastic strip or band 23' which extends through an opening 20' in the back panel 13' of the lower or corset part C'. The lower end of the elastic strip 23' is connected through two divergent non-elastic 20 tapes 32 to the upper ends of the spaced back garters 29'. As shown in Fig. 6, the lower corners of the lining 14' of the lower back panel 13' are cut away at 33 to permit the tapes 32 to pass out of this lining and connect with the garters 29'. 25

With the arrangement of Figs. 5 and 6, the lower back edge of the upper or brassière part B' of the garment is held snugly against the body at all positions, and is movably connected to the lower or corset part C' of the garment through 30 the elastic connection 23' and the garters 29'. In this modification of the invention, as well as in that shown in Figs. 1 to 4, there is no tendency for a bending movement to displace either the brassière or corset parts away from their proper 35 supporting positions on the body since relative movement of the garment parts is permitted by the elastically extensible connection.

I claim:

1. In a foundation garment of the type described, a lower corset part comprising front and back sections, a pair of garters attached at back section at a point adjacent the lower edge thereof, an upper brassière part comprising a front section fixed to the front section of said lower corset part and a back section separate from the back section of said lower corset part, and means including an elastically extensible element connected between a point adjacent the lower edge of said brassière part back section and 50 a point on said garter means adjacent the connection between said garter means and said corset part back section.

2. In a foundation garment of the type described, a lower corset part comprising front and back sections, a pair of garters attached at spaced points to the lower edge of said corset part back section, an upper brassière part comprising a front section fixed to the front section of said lower corset part and a back section separate from the back section of said corset part and having a lower edge overlapping the upper edge of said corset part back section, said corset part back section having an opening therein and a lining behind said opening, and means 60 including an elastically extensible element passing through said opening and connected between the lower edge of the back section of said brassière part and said spaced garters.

3. In a foundation garment of the type described, a corset part adapted to completely encircle the lower part of the body and having vertically-spaced stays, a brassière part adapted to completely encircle the upper part of the body, the front sections of the corset part and the 75

- brassière part being sewed together, the brassière part being separate from the corset part at the back and having its lower edge overlying the upper portion of the back of the corset part, and 5 a single connection, elastic at least in part, between the lower portion of the center of the back of the brassière part and the corset part, at least a part of said connection extending behind the corset part and secured thereto adjacent said stays, whereby the corset and brassière parts are held against relative movement at the front, but are elastically connected together at the back where relative movement between said parts may take place when the wearer bends forward.
- 10 4. In a foundation garment of the type described, a corset part adapted to completely encircle the lower part of the body, said corset part having an opening in the back thereof, a brassière part adapted to completely encircle the up- per part of the body, the front sections of the corset part and the brassière part being sewed together, the brassière part being separate from the corset part at the back and having its lower edge overlying the upper portion of the back of the corset part, and a single connection between the lower portion of the center of the brassière part and the corset part, said connection comprising a downward extension at the center of the back of the brassière part and an elastic 10 part connected thereto, said connection passing through said opening in the back of the corset part, whereby the corset and brassière parts are held against relative movement at the front but are elastically connected together at the back 15 where relative movement between said parts may take place when the wearer bends forward.

JACOB L. ALBERTS.

Certificate of Correction

Patent No. 2,051,065.

August 18, 1936.

JACOB L. ALBERTS

It is hereby certified that errors appear in the printed specification of the above numbered patent requiring correction as follows: Page 1, second column, line 30, for "empodying" read *embodying*; line 45, for "prassière" read *brassière*; page 2, second column, line 42, claim 1, for the words "a pair of garters" read *garter means*; and same line and claim for "at" read *to said*; and that the said Letters Patent should be read with these corrections therein that the same may conform to the record of the case in the Patent Office.

Signed and sealed this 27th day of October, A. D. 1936.
